UNITED STATES PATENT OFFICE

HUGH LOGIE ALLAN, OF BURMAH, BRITISH INDIA, ASSIGNOR TO THE BURMAH OIL COMPANY LIMITED, OF GLASGOW, SCOTLAND, A BRITISH CORPORATION

WAX SWEATING PLANT

Application filed July 25, 1930, Serial No. 470,640, and in Great Britain October 2, 1929.

This invention relates to apparatus for the heat treatment of wax and wax mixtures, comprising a vessel having means for charging the same with wax or wax mixture, which is supported within the vessel without the use of water as a wax support, means being provided for withdrawing successive portions of the mixture during the heat treatment, and means being also provided for uniformly heating or cooling the wax throughout the vessel.

Such apparatus is disclosed in the specifications of United States Patents Nos. 1,504,923 and 1,743,746, the latter patent disclosing the use of a series of transverse pipe coils through which a heating or cooling fluid is circulated, said pipe coils being spaced closely throughout the wax mass under treatment.

The present invention contemplates the employment of a multiplicity of transverse or horizontal pipes straight throughout their length and connected at their ends in groups to inlet and outlet chambers.

The present invention contemplates the provision of a deep closed vessel of large capacity having its external walls insulated or lagged to enable the vessel to be used in the open for the heat treatment of wax or wax mixture, instead of being enclosed in a specially heated building as has been heretofore proposed.

The staggering of the pipes closely spaced throughout the mass of wax under treatment, not only leads to improved heat transference, but provides a more efficient support for the mass of wax during the sweating process.

The apparatus may be of the known type comprising a closed upright vessel having partitions dividing it into a plurality of superposed wax containing compartments in which the wax is supported without the use of water as a wax support, and the present invention therefore further consists in providing the several superposed compartments of an apparatus of the type described with superposed rows of straight transverse pipes in each compartment, a heating or cooling fluid being circulated through the said pipes, which are closely spaced throughout the mass of wax in each compartment.

In order that the invention may be more clearly understood, reference is hereinafter made to the accompanying drawings which illustrate one construction of apparatus according to the invention.

Fig. 1 is a vertical sectional elevation through part of the apparatus. In this view only one set of pipes is illustrated in full line, the other sets of pipes being denoted by broken lines.

Fig. 2 is a plan view of the apparatus shown in Fig. 1 with the cover plate removed.

Fig. 3 is a fragmentary front view of the apparatus shown in Figs. 1 and 2, showing the water inlet and outlet headers at the opposite ends of the pan or vessel.

Fig. 4 is a part sectional elevation on the line 4—4 of Fig. 2, showing the steaming-out header.

Fig. 5 is a part sectional elevation showing an alternative construction of the charging and run-down passages.

Fig. 6 is a sectional plan view of the charging and run-down passages shown in Fig. 5.

The apparatus shown is particularly adapted for use where the circulating fluid is of a corrosive nature. The vessel 36 is divided into a plurality of closed wax compartments 37 of rectangular form vertically superimposed, the divisions or diaphragms forming the bottom plates 38 of the compartments being sloped downward to one side. A false bottom 39 of reticulated metal, metallic gauze or the like, forming a support for the mass of wax or wax mixture during heat treatment, is fitted slightly above the bottom plate 38 of each compartment 37 and may be supported therefrom by means of corrugations 40 formed in the said bottom plate 38 or by other suitable means. Each vertical end of the apparatus is of cellular construction consisting of vertical tube plates 41 and horizontal plates 42 dividing the spaces between the tube plates 41 and the outer shell 36 into a series of cells or headers 43, 44, 45 and 46 by means of which circulating fluid is led to and received from a number of straight horizontal pipes 47, preferably of mild steel of about $\frac{3}{4}$ " bore, disposed throughout the wax space in each compartment 37 in substantially hori-

zontal rows, the horizontal pitch in each row being about four inches and the vertical pitch of the rows being about two inches, adjacent horizontal rows being staggered in the 5 plan view so as to afford a maximum support for the wax mass during heat-treatment. The ends of the horizontal tubes 47 may be expanded into holes formed in the vertical end plates 41 of the apparatus or may be secured by screwed and packed ferrules or by any other known means. The circulating fluid enters the cell or header 43 and after passing in one direction through one set of tubes 47 into the cell or header 44, returns through the 10 higher set of tubes into the cell or header 45 and from thence through the uppermost set of tubes into the outlet cell or header 46. According to the cross-sectional area of the apparatus one or more vertical charging 20 and rundown passages 48 are formed in or provided at the vertical side towards which the bottom plates 38 slope downward, for the purpose of introducing the liquefied wax or wax mixture prior to treatment, for supercharging by introducing additional liquid wax or wax mixture to compensate for shrinkage of the original charge during the cooling phase, and for conducting away to an outlet pipe or pipes 49 at the bottom of the 25 said vertical passages 48 oil or liquid wax discharged during the process of heat-treatment. The said vertical passage or passages 48 may be rectangular in horizontal section and may be fitted internally with pipes 50 (Figs. 1 and 2) or ducts 51 (Figs. 5 and 6) 30 adapted to receive heating fluid for the purpose of maintaining the wax mixture contained in the vertical passages 48 in liquid state when required. At the side of the apparatus remote from the charging and rundown passages 48 is a series of air vents 52 located at or near the top of each wax space 37 and connected to an external header 53 adapted to control admission or discharge 35 of air to or from the interior of the apparatus. One or more headers 54 are provided for injecting steam or other heating fluid into the space between the bottom 38 of each wax compartment 37 and the false bottom 39, 40 and into the space above the false bottom 39 through jet connections 55 to facilitate the melting out of the residual wax after heat-treatment. The horizontal pipes 47 for circulation of heating or cooling fluid may be supported at various points in their length 45 by means of vertical diaphragms 56 perforated to correspond with the arrangement of holes in the end plates 41 of the apparatus. On the top cover 57 of the apparatus are located relief valves 58 or other means for relieving the apparatus of internal pressure exceeding a predetermined limit.

The series of headers 43 (Fig. 3) are supplied with circulating fluid through connections 59 connecting the headers 43 with a

main inlet header 60 situated close to the vertical end of the apparatus. The outlet headers 46 are similarly connected by means of connection pipes 61 leading the fluid away from the headers 46 to a main outlet header 62.

A central steam pipe 63 extends through the air inlet and outlet header 53 for freeing the header of solidified wax and a similar steam pipe 64 is fitted within the steam 75 headers 54 for the same purpose, the wax being run off through drain pipes 65.

Stiffeners 66 are fitted beneath each diaphragm or bottom plate 38 inside the compartments and extend centrally from end to end of the compartment 37 and may comprise flanged plates, iron angles or the like. These stiffeners are perforated to permit passage of air and/or wax mixture from one side to the other.

The vertical diaphragm plates 56 have their corners cut away to provide air passages 67 between the compartments formed on each side of the plates 56 in order that the air supplied by the air header 53 may freely circulate through the whole compartment.

By the use of pipes straight throughout or for the greater part of their length air may be expelled during passage of the fluid, whereby internal corrosion of the piping is reduced 95 to a minimum. The apparatus is particularly adapted for installing in the open without enclosure or protection by special building, but if preferred it may be installed inside a building of any known type or construction.

The apparatus may consist of a single container or vessel of any desired capacity, the vessel corresponding to one of the wax compartments 37, that is to say, without being 105 sub-divided into superposed compartments or into adjacent compartments by the vertical diaphragm plates 56.

Claims:

1. Apparatus for the heat-treatment of 110 wax or wax mixture comprising a wax containing vessel, a wax support above the bottom thereof, a multiplicity of straight transverse heating or cooling fluid circulating pipes arranged in superposed groups each 115 in superposed transverse rows in said vessel, an inlet chamber communicating with one end of the lowermost group of pipes, an intermediate chamber connecting the opposite end of the lowermost group of pipes with a superjacent group of pipes, and an outlet chamber connected to the opposite end of the superjacent group of pipes to cause the fluid to flow through the groups of tubes 120 in series.

2. Apparatus for the heat-treatment of 125 wax or wax mixture comprising a wax containing vessel, a wax support above the bottom thereof, a multiplicity of straight transverse heating or cooling fluid circulating 130

5 pipes arranged in superposed groups each in superposed transverse rows in said vessel, an inlet chamber communicating with one end of the lowermost group of pipes, an outlet chamber communicating with the uppermost group of pipes, and intermediate chambers connecting the ends of said lowermost and uppermost groups of pipes to intermediate groups of pipes at alternate ends to cause the 10 fluid to flow through the groups of tubes in series.

15 3. Apparatus for the heat-treatment of wax or wax mixture comprising a wax containing vessel, a wax support above the bottom thereof, a multiplicity of straight transverse heating or cooling fluid circulating pipes arranged in superposed groups each in superposed transverse rows in said vessel, an inlet chamber communicating with 20 one end of the lowermost group of pipes, an outlet chamber communicating with the uppermost group of pipes, and intermediate chambers connecting the ends of said lowermost and uppermost groups of pipes to intermediate groups of pipes at alternate ends, said chambers being external to said wax-containing vessel to cause the fluid to flow through the groups of tubes in series.

25 4. Apparatus for the heat-treatment of wax or wax mixture comprising a wax-containing vessel having opposite ends of cellular construction each consisting of a vertical outer shell, an inner vertical tube plate and horizontal plates dividing the space between the shell and tube plate into a series of superposed cells, a multiplicity of straight transverse pipes extending between the tube plates, a heating or cooling fluid inlet pipe connected to one of the lowermost cells and 30 an outlet pipe connected to one of the uppermost cells, whereby fluid passes from one cell in one direction through one set of pipes into a cell at the opposite end of the vessel and returns through a higher set of pipes 35 into another cell, finally escaping through the outlet pipe.

40 5. Apparatus for the heat-treatment of wax or wax mixture comprising a rectangular wax containing vessel, the bottom of which slopes towards one side, a vertical charging passage at the side of the vessel to which the bottom slopes and opening into 45 said vessel, a supply pipe at the upper end of said passage, an outlet at the lower end of said passage, a wax support above the bottom of said vessel, a multiplicity of straight transverse heating or cooling fluid circulating pipes arranged in superposed 50 transverse rows in said vessel and parallel with the side of the vessel to which the bottom slopes, inlet and outlet chambers at the ends of said vessel communicating respectively with the lowermost and uppermost 55 groups of pipes, and intermediate end chambers 60 connecting the pipes in groups at alternate ends.

6. Apparatus for the heat-treatment of wax or wax mixture comprising a rectangular wax-containing vessel, the bottom of which slopes towards one side, a wax support above the bottom of said vessel, a multiplicity of straight transverse heating or cooling fluid circulating pipes arranged in superposed transverse rows in said vessel and parallel with the side of the vessel to which the bottom slopes, inlet and outlet chambers at the ends of said vessel communicating respectively with the lowermost and uppermost groups of pipes, intermediate end chambers connecting the pipes in groups at alternate ends, a vertical charging channel of rectangular section open on one side to the vessel at the side to which the bottom of the vessel slopes, a supply pipe at the upper end of said passage, an outlet at the lower end of said passage, a steaming chamber formed by a vertical partition in said passage, and steam inlet and outlet connections to said chamber.

7. Apparatus for the heat-treatment of wax or wax mixture comprising an elongated rectangular wax-containing vessel, the bottom of which slopes towards one side, vertical partitions at right angles to said side and dividing said vessel into chambers which communicate with each other through said partitions, a wax support above the bottom of said vessel, a multiplicity of straight transverse heating or cooling fluid circulating pipes passing through said partitions and arranged in superposed transverse rows in said vessel and parallel with the side of the vessel to which the bottom slopes, inlet and outlet chambers at the ends of said vessel communicating respectively with the lowermost and uppermost groups of pipes, intermediate end chambers connecting the pipes in groups at alternate ends, a vertical charging passage for each of said chambers and opening thereto, a supply pipe at the upper end of each passage, and an outlet at the lower end of each passage.

8. Apparatus for the heat-treatment of wax or wax mixture comprising a closed upright rectangular shell, transverse diaphragms dividing said shell into superposed wax compartments, the bottom of said shell and said diaphragms sloping downwards towards one side, wax supports above said bottom and diaphragms, inner vertical tube plates spaced from each end of said shell, horizontal plates dividing the space between the shell and each tube plate into a series of superposed cells, a multiplicity of straight transverse pipes extending between the tube plates in each compartment, inlet and outlet connections to the group of pipes in each compartment, whereby heating or cooling fluid may be circulated in one direction through the lowermost set of pipes of each

group, and pass in alternate directions through higher sets of pipes of each group before finally escaping, a vertical charging passage open to the side of the vessel to which the diaphragms slope, a supply pipe connected to the upper end of said passage, and an outlet at the lower end of said passage.

9. Apparatus for the heat-treatment of wax or wax mixture comprising a closed upright rectangular shell, transverse diaphragms dividing said shell into superposed wax compartments, the bottom of said shell and said diaphragms sloping downwards towards one side, wax supports above said bottom and diaphragms, inner vertical tube plates spaced from each end of said shell, horizontal plates dividing the space between the shell and each tube plate into a series of superposed cells, a multiplicity of straight transverse pipes extending between the tube plates in each compartment, inlet and outlet connections to the group of pipes in each compartment, whereby heating or cooling fluid may be circulated in one direction through the lowermost set of pipes of each group, and pass in alternate directions through higher sets of pipes of each group before finally escaping, a vertical charging passage open to the side of the vessel to which the diaphragms slope, a supply pipe connected to the upper end of said passage, an outlet at the lower end of said passage, a series of air vents near the top of each compartment at the side opposite to the charging passage, a header connecting said vents, means for injecting steam into said compartments above and below the wax supports.
